UNITED STATES PATENT OFFICE

118,259

DESIGN FOR A MAKE-UP CABINET

Ernest O. Carlson, Rockford, Ill.

Application October 30, 1939, Serial No. 87,940

Term of patent 14 years

To all whom it may concern:

Be it known that I, Ernest O. Carlson, a citizen of the United States, residing at Rockford, in the county of Winnebago and State of Illinois, have invented a new, original, and ornamental Design for a Make-Up Cabinet, of which the following is a specification, reference being had to the accompanying drawing, forming part thereof.

In the drawing:

Fig. 1 is a perspective view of a make-up cabinet showing my new design with the mirror in raised position, and

Fig. 2 is a fragmentary front elevational view thereof with the mirror in lowered position and with a portion of the cabinet shown broken away for convenience of illustration.

The dominant features of my design reside in the portions shown in full lines.

I claim:

The ornamental design for a make-up cabinet, substantially as shown and described.

ERNEST O. CARLSON.
